METHOD OF POSITIONING GRINDING DISKS
Herbert J. Fallon, Beloit, Wis., assignor to Besly-Welles Corporation, South Beloit, Ill., a corporation of Illinois

Filed Nov. 24, 1959, Ser. No. 855,051
4 Claims. (Cl. 51—281)

This invention is in the field of grinding and is concerned with a method of sizing for accurately positioning a grinding wheel in a disk grinder or the like.

A primary object of the invention is a method of sizing which does not require physical contact with the faces of the grinding disk in a disk grinder.

Another object is a gauging method which uses an air jet to sense the position of the face of the disk.

Another object is the use of a nozzle which is movably mounted in a double disk grinder so that the disks may be moved in somewhat preparatory to a dressing operation.

Another object is a gauging method for double disk grinders which is particularly beneficial for or with an automatic dresser.

Another object is a gauging method which senses the disk face in an accurate location.

Another object is a gauging or sizing method which may be used with a rotary, oscillating through feed, or any suitable feeding mechanism.

Other objects will appear from time to time in the ensuing specification and drawings in which:

FIGURE 1 is a schematic or diagrammatic layout of the invention;

FIGURE 2 is a perspective of a portion of the grinder;

FIGURE 3 is a side view, on an enlarged scale, of the air nozzles previously shown schematically; and

FIGURE 4 is a section along line 4—4 of FIGURE 3.

In FIGURE 1, the disks 10 of a double disk grinder have been shown opposite each other spaced apart a predetermined distance so that the workpieces may be passed between the disks to grind accurate parallel opposite surfaces by direct contact with the disk faces 12. The disks are mounted on shafts 14 and are rotated by any suitable drive. Nor is the make-up of the specific grinding disks important, other than that they may be suitable abrasive grinding wheels.

I show two air nozzles or jets 16 positioned between the grinding disks, back to back, with openings so that the air jets from the nozzles will be directed in opposite directions. It will be noted in FIGURE 1 that the nozzles are opposite the faces of the disks and the air jets from the nozzles will strike or impinge against the faces 12 of the disks. The nozzles are mounted on a suitable support 18 and are supplied with air through suitable conduits or tubes 20 from controllers 22. Air from the air source, such as a compressor or the like, not shown, is supplied to each of the controllers by suitable connections 24 and the air is monitored or controlled by the controller and in turn is passed through the tubes 20 to the nozzles 16. The controllers may be of the type presently sold by Moore Products Company of Philadelphia, Pa., and, in detail, are not important to this invention. Suffice it to say that the controller basically senses the variations in a pressure signal and converts it to an electrical signal by operating switch contacts or the like. The controllers sense the pressure of the air passing through the system to the nozzles and in response to that pressure control the infeed of the grinding disks toward each other. It will be noted in FIGURE 1 that the grinding disks are constructed to be moved toward each other as the faces wear away during grinding, such movement being indicated by arrows. The controllers each send a signal to the disk feeding mechanism, to be set forth more in

2

detail hereinafter, through suitable leads 26. The controllers may be supplied with current through suitable leads 27 from an outside power source.

Workpieces are passed between the faces 12 of the grinding disks. As the disks break down or wear away, the faces will move farther and farther away from the jet outlets of the nozzles 16. This reduces the resistance to the outflow of air from the nozzles thereby causing the pressure of the air in the system to drop. The controllers can be set up so that in response to a predetermined low pressure, a signal will be sent through electric leads or otherwise, to the infeeding mechanism which will move either one or both disks toward each other. As the disk face approaches the nozzle opening, it will offer more resistance to the air flow. This will cause the air pressure in the system to increase. A controller may be set up so that at a predetermined high pressure the infeed will cease.

The grinding wheel infeed mechanism may be set so that in response to a signal from the controller, it will automatically infeed a set amount. As soon as the air pressure in the system drops to a predetermined low, the controller will send a signal to the infeed mechanism causing it to infeed a predetermined amount. The infeed of the wheel face will cause the air pressure in the system to rise, and if it rises above a desirable minimum or within a preset range, no further infeeding will be necessary. But if it is still below, the controller will again send a signal causing another infeed until the desirable spacing is obtained.

In FIGURE 2, one of the disks 10 is shown with its nozzle 16, it being understood that the showing in FIGURE 2 could be either disk of FIGURE 1. The disk is rotatably mounted in a quill 28 and is driven by a drive 30 which leads to an electric motor or the like, not shown. The quill is constructed to be moved axially by cylinders 32 which traverse it in an axial direction rapidly back and forth between grinding and dressing positions. As shown in FIGURE 1, the wheels are in grinding position and are closely spaced. When the wheels have broken down sufficiently so that dressing is required, the quills are moved outwardly a predetermined amount by the quill cylinders 32 and a dresser with oppositely disposed diamonds, not shown, is passed between them to dress off the face of each wheel. I prefer that the two quill cylinders lie in a horizontal plane which passes through the center of the disk and spindle 14 so that the reactive forces will be counter-balanced. The quill is supported by and is constructed to slide back and forth on suitable pads 34. Since the drive 30 is intended to be stationary, I connect it to the projecting end of the disk spindle by a spline connection 36.

Mounted above the quill and connected firmly to it by a key connection or the like is a spindle lug or bracket 38 which supports an air cylinder 40. The infeed mechanism 42 is suitably supported by the frame of the machine and includes a cross shaft 44 constructed to be rotated by an automatic ratchet or clutch mechanism and drive 46 or the like connected by leads 26 to the controller to move a feed screw 48 through a suitable gear, pinion, and nut arrangement 50. Rotation of the cross shaft 44 causes the worm gear or rack 48 to move to the left in FIGURE 2 thereby moving bracket 38, quill 28 and the disk 10 axially toward the air nozzle 16. The feed screw 48 has a collar 52 which abuts a block 54 connected to the piston rod 56 of the air cylinder 40. Thus, the air cylinder 40 raises and lowers the block 54 to either position in between the bracket 38 and the collar 52 or to raise it above the collar 52 so that the quill cylinders 32 may move the quill and the grinding disk outwardly until the face of bracket 38 contacts the collar 52.

3 During normal operation, air pressure is supplied to the quill cylinders 32 so that they are thrusting outwardly or tend to pull the disks 10 outwardly away from grinding position and away from each other. This eliminates all backlash in the infeed mechanism 42. When the disk faces have broken down to a degree such that a dressing operation is desirable, first the air pressure is reversed in the quill cylinders so that the thrust is inwardly. This relieves the pressure between the various parts in the infeed mechanism and the air cylinder 40 can easily raise the block 52. Then the air pressure in the quill cylinders 32 is again reversed and since the block is up and out of the way the quill will move outwardly until the face of the bracket 38 contacts the collar 52 on the feed mechanism. Then the automatic dresser, not shown, passes between the grinding disks across the disk faces to dress them. Then the air pressure is again reversed in the quill cylinders to bring the quill and the grinding disks back to grinding position where they are more closely spaced and normal grinding starts again.

During normal operation, the air nozzles are quite close to the faces of the disks. For example, they might be at .005 inch. Since the quill cylinders are initially reversed to allow the block 54 to be raised, there is some inward movement of the disks which may be on the order of 7 or 8 thousandths of an inch. To prevent the face of the disk from contact of the nozzle, I mount the nozzle so that it will also move inwardly or in the same direction as the movement of the disk, as shown in detail in FIGURES 3 and 4. A suitable mounting bracket 58 on the frame of the grinder may have a nozzle 60 connected to it by a suitable cap 61 and mounting bracket 62 held by bolts 64 or otherwise. The second nozzle structure 66 may be mounted on the lower surface of mounting bracket 62 by a mounting bracket 68 and cap 70 connected by bolts 72 or the like. It will be noted that the upper part 73 of mounting bracket 68 is in a guideway 74 on the lower surface of the upper mounting bracket 62 and is constructed to be adjusted longitudinally in any suitable manner and held, when in position, by a bolt and slot connection indicated generally at 75.

The nozzle structure, shown in detail in FIGURE 4, includes an air cylinder 76 having a piston rod 78 extending from it. End caps 80 and 82 are separated by a sleeve type spacer 84 and are connected to it by bolts 86. The end caps 80 and 82 carry spacing pins 88 which are adjustably positioned on each side of a stop plate 90. The outer ends of the pins 88 are beveled and engage adjustable stop screws 92 which vary the position of the spacing pins 88. Stop plate 90 is against a shoulder 94 on the piston rod 78 and is held in place by a key 95. The stop plate 90 fits over a pin 96 mounted in the end cap 82 and slides back and forth on it. This prevents the piston rod 78 from rotating. The other end of the piston rod 78 supports a holder 98 for the air nozzle 16 which is keyed to it at 100. Thus, the holder 98 and air nozzle 16 will be held in position. The end of the piston rod 78 has a suitable cap nut 102 screwed to it and a bellows or diaphragm 104, held on each side by suitable O rings 106, allows for movement of the piston rod 78 and air nozzle 16 and holder 98 without leakage.

It will be noted that a slight spacing exists, as at 110, between the faces of the stop pins 88 and the stop plate 90. This is to say that the faces of the pins 88 are spaced just slightly farther apart than the thickness of the stop plate 90. Thus, the piston rod can move back and forth by an amount equal to the spacing 110. Movement of the piston rod 78 will move the nozzle holder 98 which in turn moves the nozzle 16.

The structure shown and described in relation to FIGURE 4 may be the same for both nozzle holders, although it has been specifically set forth with reference to the upper nozzle in FIGURE 3.

Relating the FIGURES 3 and 4 structure to the FIGURES 1 and 2 structure, the air cylinder 76 for moving

4 the nozzle 16 may be tied into or related directly or indirectly to the air system for the quill cylinders 32 or it may be separate but operated simultaneously with it. In any event, when the pressure in the quill cylinders 32 is reversed from what it is during grinding, so that the disks are thrust inwardly, at the same time the air in cylinder 76 is reversed so that the piston rod 78 moves to the right in FIGURE 4 and the air nozzle 16 also moves. In the position shown in FIGURE 4, the air cylinder 76 is pulling the nozzle 16 to the left, which may be assumed to be either grinding position or the position assumed at the beginning of a dressing operation.

The use, operation and function of the invention are as follows:

Whereas I have referred principally to a double disk grinder, it should be understood that many, if not all, of the novel features may be applied equally as well to a single disk grinder. Whether single or multiple, the axis of the disk or disks may be vertical, horizontal, or otherwise. Also, I have stressed automatic dressing, and it should be understood that the dressing may be any suitable manual arrangement or semi-automatic. Additionally, the infeed of the disk or disks has been characterized as automatic, and it should be understood that it could be manual. In this sense, the signal from the controller or controllers could energize a suitable light, bell, or any suitable manifesting device in response to which the operator could manually infeed, or energize the infeed mechanism. Or any combination of the above could be used.

While the movable nozzles shown in FIGURE 4 are intended primarily to be used in conjunction with automatic dressing, it should be understood that the nozzles in FIGURE 1 could be adjustably mounted, to be adjusted by hand and preset for any particular grinding operation. But when grinding or dressing, the nozzle or nozzles would be considered fixed. This is true of either a single or multiple disk grinder.

In the past, an air nozzle has been used against the periphery of the grinding wheel in a centerless grinder, but the nozzle was moved toward the grinding wheel, as the wheel broke down, along with a regulating or work positioning wheel. This could not be used in a disk grinder since it would involve a complete overhaul of the article feeding mechanism, be it a rotary or through feeder or what have you, as well as extreme complication in adjusting the related mechanism.

Accurate positioning of the grinding wheels has proved particularly troublesome in the past. This is particularly true of double disk grinders in which the sides or faces of the wheels are used for grinding instead of the periphery. The faces are closely spaced and are opposite each other and the work may be sheared or passed between the grinding faces. As the faces break down, the wheels are fed inwardly toward each other to compensate for wheel wear.

In the past, hardened feeler fingers or indirect measuring gauges have been used to feel or sense the position of the wheel face followed by some sort of an infeeding mechanism to compensate for wheel wear. But this involves physically touching the wheel face which inevitably results in wear on the item being contacted or in some indirect method such as gauging the workpiece or otherwise.

I would prefer that the air nozzles be located well within the periphery of the grinding disks, for example on the order of 1 1/2 inches so that the jets will impinge against the disk faces beyond or inside of the area at the peripheral edge which is broken down rapidly due to shearing in of the workpieces. I also prefer that the nozzles be positioned behind or on the back side of the disks, relative to the side where the workpieces are introduced, and below the center line of the disks. This might be referred to as in the rear lower quadrant. The point is that in a double disk grinder, the disks may be tilted

back slightly in the case of a push-through feeder, and tilted both back and down in the case of a rotary feeder. In either case, the rear lower quarter is affected the least and, accordingly, any such tilting or a combination thereof would have the least effect in the rear lower quarter of the disks.

In a double disk grinder where automatic dressing is highly desirable, gauging directly from the wheel faces is very important since once the gauging devices have been set, the dresser can be accurately positioned relative to the nozzles so that when the dresser is passed between the grinding faces, the machine, so to speak, will know exactly where the new faces of the wheels are. Or the nozzles can be set accurately relative to the dresser. But in either case when the faces of the disks have been dressed off, the new plane of the faces will be accurately established relative to some fixed part of the machine. In systems which gauge or check the workpiece, the spacing between the wheel faces may be checked by gauging the workpiece and when oversize, infeeding may take place. But an oversize workpiece does not tell whether or not the wheels have broken down at the same rate or differentially. In the event that one wheel has broken down much faster than the other, an automatic dresser would remove a substantial amount from the wheel that hadn't broken down and might miss or barely touch the other. But, in the arrangement shown, the dresser and nozzle can be accurately positioned relative to each other. Then the wheels can always be brought to the air nozzles or may be positioned in predetermined relation to the air nozzles just prior to an automatic dressing operation. This insures that the dresser will dress approximately the same amount off of each wheel. The dresser referred to above is of the type having oppositely disposed diamonds or the like spaced a predetermined distance apart and the dresser has not been shown in detail in the drawings since it is well known in the art.

While I have referred to the use of two nozzles, each of which checks the face of its wheel independently, it is quite feasible to use one nozzle and thereafter the workpiece could be gauged or checked which would accurately tell the precise position of the face of the other wheel.

In the arrangement shown, the nozzles are also movably mounted so that when the thrust of the quill cylinders is reversed at the beginning of a dressing operation, the nozzles will move in the same direction to prevent contact between the face of the wheels and the nozzles. This has the distinct advantage that in a machine of the type shown backlash may be eliminated during grinding, automatic dressing may be used, and the nozzles may be positioned between the grinding faces of the disks or wheels, all without needless complication with all parts operating or being tied in together.

While I have shown and described the preferred form and suggested variations of my invention, it should be understood that suitable additional modifications, changes, substitutions and alterations may be made without departing from the invention's fundamental theme. I, therefore, wish that the invention be unrestricted, except as by the appended claims.

I claim:

1. A method of positioning the grinding disks in a double disk grinder having grinding disks rotatable about an axis with opposed faces, including the steps of directing a controlled air current from a source against each of the opposed faces of the disks, positioning each source a predetermined distance from the face of its disk, moving each source along said axis away from its grinding disk when the face of its disk comes closer to the source than the predetermined distance to prevent contact between the face of each disk and its source, feeding each disk along said axis until the increase in air pressure in its controlled air current, due to resistance offered by the face of its disk, reaches a predetermined high value, and

thereafter feeding each disk along said axis toward the other, from time to time, as the air pressure in its controlled current drops to a predetermined low value due to the face of its disk being worn away during grinding to thereby maintain an accurate spacing between the disk faces.

2. A method of positioning the grinding disks in a double disk grinder which has two co-axially mounted oppositely disposed grinding disks to grind generally parallel faces on a work part passed between the opposed faces of the disks, including the steps of directing controlled air currents from adjacent sources against the opposed faces of the disks, one air current against the face of each grinding disk, directing the air currents in opposite directions from approximately the same point between the disk faces, positioning each source a predetermined distance from the face of its disk, moving each source along said axis away from its grinding disk when the face of its disk comes closer to the source than the predetermined distance to prevent contact between the face of each disk and its source, feeding each disk axially inward in opposition to the air currents, discontinuing the disk feed when the air pressure in the current, due to the proximity of the disk face, increases to a predetermined value, feeding work parts between the disks to grind generally parallel faces thereon resulting in the disk faces breaking down, and, from time to time, feeding each disk axially inwardly toward each other against the direction of the air currents when the air pressure in the controlled current drops a predetermined amount.

3. A method of positioning the grinding disks in a double disk grinder which has two co-axially mounted oppositely disposed grinding disks rotatable about an axis to grind generally parallel faces on a work part passed between the opposed faces of the disks, including the steps of directing controlled air currents from adjacent sources against the opposed faces of the disks, applying a pressure against each disk to urge the disks apart against fixed points, reversing the applied pressures to urge the disks together against an air current in excess of a predetermined value, moving the adjacent air current sources along said axis with the disks to prevent contact therebetween, reversing the applied pressures to urge the disks further apart to dressing position, dressing the opposed faces of the disks, feeding each disk axially inward in opposition to the air currents, and discontinuing the disk feed when the pressure of the air in the current, due to the proximity of the face of each disk, increases to a predetermined value.

4. A method of positioning the grinding disk in a disk grinder in which the grinding wheel is constructed to be rotated about an axis and has a grinding face, including the steps of directing a controlled air current from a source against the face of the disk, positioning the source a predetermined distance from the face of the disk, moving the source along said axis away from the face of the disk when the face of the disk comes closer to the source than the predetermined distance to prevent contact between the face of the disk and the source, feeding the disk along said axis until the increase in air pressure in its controlled air current, due to resistance offered by the face of the disk, reaches a predetermined high value, and thereafter feeding the disk along said axis, from time to time, as the air pressure in the controlled air current drops to a predetermined low value due to the face of the disk being worn away during grinding to thereby maintain the face of the disk in an accurate position.
